UNITED STATES PATENT OFFICE.

JOSEPH SHERMAN, OF BURLINGTON, NEW JERSEY.

DESIGN FOR A FRUIT-BOX.

Specification forming part of Design No. 5,292, dated September 26, 1871.

To all whom it may concern:

Be it known that I, JOSEPH SHERMAN, of Burlington, county of Burlington, State of New Jersey, have invented or produced a Design for a Fruit-Box, of which the following is a specification:

In the accompanying drawing, Figure 1 is a side view of a fruit-box made in accordance with my design; Fig. 2, a plan view; and Fig. 3, a side view, looking in the direction of the arrow, Fig. 2.

The box has four inclined sides, A, joined to each other at their corners by four narrower inclined sides or corner pieces, b, arranged at an angle of forty-five degrees in respect to the said sides A. All of the sides and corner pieces are

inclined inward toward the bottom piece c, which is suitably secured within the box, the whole forming a tapering receptacle for containing and transporting fruit.

I claim—

The design for a fruit-box, substantially as described, and illustrated in and by the accompanying drawing.

In testimony whereof I have signed my name to this specification in the presence of two subscribing witnesses.

JOSEPH SHERMAN.

Witnesses:

J. B. HARDING,
HARRY SMITH.
